UNITED STATES PATENT OFFICE.

SAMUEL HAYWARD, OF BOSTON, MASSACHUSETTS.

CHAIR.

SPECIFICATION forming part of Letters Patent No. 374,250, dated December 6, 1887.

Application filed August 27, 1887. Serial No. 248,038. (No model.)

To all whom it may concern:

Be it known that I, SAMUEL HAYWARD, of Boston, in the county of Suffolk and State of Massachusetts, have invented certain new and 5 useful Improvements in Chairs, of which the following, taken in connection with the accompanying drawings, is a specification.

My invention relates to that class of chairs which have provision for varying the inclination of the back and the height of the seat, and is an improvement upon the invention shown and described in the Letters Patent No. 363,389, granted to me May 24, 1887; and it consists in certain novel features of construction, arrangement, and combination of parts, which will be readily understood by reference to the description of the drawings and to the claims to be hereinafter given, and in which my invention is particularly pointed out.

20 Figure 1 of the drawings is a central vertical section of a chair embodying my invention, the cutting plane being parallel, or nearly so, to the side arms of the chair, the parts being in position to maintain the seat at its highest 25 elevation and the back in its most nearly upright position. Fig. 2 is a vertical section of a portion of the chair, the cutting plane being through the center of one of the side frames and parallel to the plane of section of Fig. 1. 30 Fig. 3 is a plan of the turn-table by means of which the chair is supported upon the central column and may be swiveled about the same, and Fig. 4 is a detail illustrating the manner of constructing and hanging the pivoted rear 35 leg or truck-carrying lever.

In the drawings, A A are the side frames, provided with the arms B and connected together by the tie-girts a, b, c, and d. C is the seat, and D the back. Beneath the seat C is 40 the gear-wheel E, mounted upon a pendent stud set in the metal tie E², and having teeth upon the under side of its rim to engage with the teeth of the pinion F, by which it is rotated, and provided with teeth upon its periphery to engage with the teeth of the pinions e e, secured upon the screws f f, mounted in bearings in the tie E², and the castings G, fitted to slots in the lower portions of the side frames, A A, all of the foregoing, except the 45 last-mentioned castings, being constructed, arranged, and operating substantially the same as described in the before-cited Letters Patent.

The lower edges of the side frames, A A, are slotted nearly their entire lengths from front to rear to receive the castings G, which are 55 firmly secured in position in said slotted frames by screws or otherwise, and have pivoted to their front ends the table or platform H, composed of a circular center having four projecting arms, g g and h h, and two side plates 60 or bars, i i, each connecting an arm, g, with an arm, h, and projecting to the rearward of arm h, and having formed upon the upper edge of said rearward projection an inclined cam-surface, j, all cast in one piece. 65

The table or platform H is provided with the trunnions or journals k k, (see Fig. 3,) by which it is pivoted to the front ends of the castings G, and with the downwardly-projecting annular lip l, to inclose the upper end 70 of the central pedestal, I, upon which said table or platform rests, and about which it may be revolved, if desired, or to which it may be secured against revolution by means of a bolt, (shown in dotted lines in Fig. 1,) said platform being secured against accidental displacement by means of the spindle J, firmly secured in said platform and extending downwardly therefrom through the bearing J', formed in the pedestal I, a pin, m, being inserted through said spindle below said bearing to prevent its withdrawal therefrom, all as 75 shown in Fig. 1.

The rear ends of the castings G are bifurcated, and have fitted in and pivoted to said 80 forked ends the metal levers n, the upper ends of which are connected by the links o and o', respectively, to the lever ends of the side bars of the pivoted back D and to the non-revolving nuts p, fitted to the screws f f, and movable vertically by the revolution of said screws, 85 all as shown in Fig. 2.

The levers n n project below their pivotal connections with the casting G, and are connected by the rod q, upon which is mounted 90 near said levers the anti-friction trucks r r, which rest upon the cam-surfaces j, along which they roll as the nuts p are raised or depressed, to change the angle of the levers n n and, through them, the angles of the back and 95 seat of the chair.

The rear portions of the side frames, A A, are slotted to receive the lower end of the side bars of the back D, the upper ends of the le-

vers *n n*, the links *o* and *o'*, the nuts *p*, and the screws *f f*, the forward vertical end of said slots having secured therein the metal plates *s*, against which the forward sides of the nuts *p* bear for the purpose of relieving the lateral pressure upon the screws *f f*, as shown in Fig. 2.

The lower arms of the levers *n n* are extended below the trucks *r r*, and have their lower ends adapted to receive a caster-truck, *t*, said arm being of such a length that the caster-wheel will touch or nearly touch the floor when the back and seat are tilted to their greatest inclination, as shown in Fig. 2, thus 15 broadening the base at the time when the greatest stability is required.

The lower arms of the levers *n n*, which are thus made at certain times to serve as rear legs to the chair, are covered with a casing of 20 wood, *u*, of the same kind as the body of the chair-frame, and may be carved to any desired design. By this construction of the chair-leg I am enabled to make a very strong adjustable 25 leg that shall be massive in appearance and comparatively light, and by fitting it to the forked end of the casting *G*, I obviate the danger of cramping the leg by the swelling or shrinking of the wooden side frame.

In another application of even date, Serial 30 No. 248,039, herewith, a central pedestal and a table or platform are shown of substantially the same construction as those shown in the present application; but in that case the platform was pivoted at its front side to the lower 35 arms of a pair of pivoted and vibratory levers, so that as the screws were revolved the whole chair-seat was raised or lowered, the rear portion, however, being moved a greater distance than the front portion, while in this case the 40 platform is pivoted directly to the chair-frame at its front side, and when the screws are revolved the rear of the seat is raised or lowered without changing the height of the front of the seat.

45 The pedestal *I* is provided at its upper end with an upwardly-projecting annular lip, *v*, having an exterior diameter somewhat less than the interior diameter of the annular lip *l* on the under side of the table or platform *H*, so that when the said table or platform is 50 placed in position on said pedestal an annular chamber will be formed between them, in which may be placed a series of anti-friction rolling supports in the form of balls, as shown 55 at *w*, or rolls, as shown at *w'* in Fig. 1.

I have shown and described anti-friction revolute trucks as the preferred means of supporting the rear levers *n n* upon the cam-surfaces *j*; but said trucks might be fixed upon 60 their bearings so as to be non-revolute and slide along said cam-surfaces with fairly good results and without affecting the principles of my invention, and therefore I do not wish to be limited in my claims to the use of revolving trucks for such supports.

65 The operation of my invention will be read-

ily understood from the foregoing without further description here.

What I claim as new, and desire to secure by Letters Patent of the United States, is—

70 1. The combination, in a chair, of a pivoted back, two independently-pivoted levers, a pair of revolute screws each carrying a non-revolute nut, links connecting the upper ends of said levers with said nuts and with the pivoted back, a table or platform pivoted at its front side to the side frames of the chair and provided with rearwardly-projecting plates having inclined cam-surfaces, and a pair of laterally-projecting bearing-surfaces carried 75 by the lower arms of said levers, and arranged and adapted to rest upon and move along said cam-surfaces as said screws are revolved to raise or lower the rear edge of the seat and vary the inclination of the back.

80 2. The combination, in a chair, of a pivoted back, two independently-pivoted levers, a pair of revolute screws, a pair of non-revolute nuts fitted to and movable by said screws, suitable links connecting the upper ends of said levers with said nuts and back, a table or platform pivoted at its front side to the side frames of the chair and provided with rearwardly-projecting plates having inclined cam-surfaces, a pair of laterally-projecting bearing-surfaces 85 carried by the lower arms of said levers, and arranged and adapted to rest upon and move along said cam-surfaces as said screws are revolved to raise or lower the rear edge of the seat and vary the inclination of the back, and 90 a central pedestal or support fitted to said table or platform by a swivel-connection.

95 3. The combination, in a chair, of a pivoted back, two independently-pivoted levers, a pair of revolute screws, a pair of non-revolute 100 nuts fitted to said screws, links connecting the upper end of said levers with said nuts and back, a table or platform pivoted at its front side to the side frames of the chair and provided with rearwardly-projecting plates having inclined cam-surfaces, a pair of laterally-projecting bearing-surfaces carried by the lower arms of said levers, and arranged to rest upon and move along said cam-surfaces to raise 105 or lower the rear edge of the chair-seat, a central pedestal fitted to a circular bearing in the under side of said table or platform, and a series of revolving anti-friction supports interposed between said table or platform and pedestal, substantially as described.

110 4. The combination, in a chair, of a pivoted back, two independently-pivoted levers, a pair of revolute screws, a pair of pinions secured one upon each of said screws, a spur gear-wheel for revolving said pinions and screws, 115 a pinion engaging said spur-gear and provided with means for revolving the same, a pair of non-revolute nuts fitted to said screws, links connecting the upper ends of said levers to said nuts and back, a table or platform pivoted at its front side to the side frames of the chair and provided with rearwardly-project-

ing plates having inclined cam-surfaces, and a pair of laterally-projecting bearing-surfaces carried by said levers, and arranged to rest upon and move along said cam-surfaces as the 5 screws are revolved to raise or lower the rear edge of the chair-seat.

5. In a chair having pivoted legs or supporting-levers, the combination of slotted side frames of wood, a forked metal bar secured in 10 said slot and extending from front to rear of said frame, and a leg or lever pivoted in the fork of said metal bar, the body of which is

made of metal and the lower or outer arm of which is incased in wood, substantially as described.

In testimony whereof I have signed my name to this specification, in the presence of two subscribing witnesses, on this 23d day of August, A. D. 1887.

15 SAMUEL HAYWARD.
